UNITED STATES PATENT OFFICE

2,503,675

BED

George D. Lunbeck, Napa, Calif.

Application May 24, 1946, Serial No. 671,932

2 Claims. (Cl. 5—136)

1

This invention relates to beds.

An object of the invention is to provide a bed which is particularly adaptable for use by animals such as dogs.

Another object of the invention is to provide a bed for dogs, cats, and the like, which is so constructed as to be foldable into a small space when not in use.

A further object of the invention is to provide a folding bed for household pets such as cats and dogs, which is simple in construction, inexpensive to manufacture, and effective in operation, being easily opened out for use, and then folded up into a relatively small floor space when it is to be moved aside.

Other objects and advantages of my invention will appear from the following description of a preferred embodiment thereof as illustrated in the accompanying drawings, and in which,

Figure 1 is an end elevation of my invention as seen from the right hand side of Figure 2, the bed being opened out.

Figure 2 is a side elevation in section, of the bed shown in Figure 1 as seen from the left side of Figure 1, but along line 2—2 of Figure 1.

Figure 3 is a plan view of the bed shown in Figure 1.

Figure 4 is a side elevation of the bed folded up, as might be seen from the left side of Figure 1.

Figure 5 is an elevational view in fragment of the bed as might be seen along line 5—5 of Figure 3, but with the side rails removed, and

Figure 6 is a sectional view in fragment, taken in a vertical plane perpendicular to the plane of the head board and through the spring fastener at the top of the head board, showing the method of fastening the foot board to the head board.

Referring now to the drawings, there is a head board member 2 the lower end 4 of which is bifurcated to form two legs 6 and 8 upon which the head board rests on the floor 10. A horizontal head rest member 12 is secured at its rearward edge 14 to the head board 2 and is supported along its left and right side edges 16 and 18 by left and right side members 20 and 22 which are suitably rounded at their upper right hand corners 24 as seen in Figure 2. The side members 20 and 22 have downward extensions 26 and 28 respectively for furnishing support for the horizontal member 12, and the side members 20 and 22 are secured along their head end edges 30 to the abutting face of head board 2 in any suitable manner.

2

Thus, taken alone, the assembly comprising the head board 2, the horizontal head rest member 12, and the two side members 20 and 22, supported on the four legs 26, 28, 6 and 8, form a stable unit which is not readily tipped over, and as will be described below, supports the remainder of the bed when folded, the said unit being the relatively stationary part of the bed.

At the foot of the bed is a foot board 32 secured to the foot ends 34 of left and right side rails 36 and 38, with floor boards 40 secured to and bridging across the lower edges of the side rails as shown best in Figures 2 and 3. The upper corners 42 of the head ends of the side rails are rounded as shown in Figures 2, 3 and 4. The side rails extend toward the head end of the bed outside of the side members 16 and 18, being pivoted to the side members by means of pins or dowels 44 extending through aligned holes in the members 16, 18, 36 and 38, so that the movable assembly comprising the foot board, the side rails, and the floor boards may be pivoted counterclockwise, as shown in Figure 2, about the pivots 44 thus tilting the movable assembly up to the position shown in Figure 4 and off the floor.

The foot end legs 46 and 48 are pivoted at their upper ends to the foot board 32 by means of hinges 50 and have their lower ends 52 resting upon the floor to support the foot end of the bed. As will be observed in Figures 1 and 2, the upper edge 54 of the foot board 32 projects upward slightly above the upper edges 56 of the side rails, a metal socket 58 being inserted in a suitable recess in the surface 60 of the foot board 32.

A lateral support strip 57 is secured to the upper edge of the face of the headboard. The upper edge 62 of the headboard 2 has a matching spring pressed plunger 64 projecting out of a suitable recess in the said edge of the head board, as shown in Figures 1, 2, 3 and 6, so that as the movable unit of the bed assumes the upright position shown in Figure 4, the spring pressed plunger 64 engages in the socket 58, thus reliably holding the movable unit in engagement with the stationary unit.

Since the floor boards only extend from the foot board to location 66, it will be observed that as the movable unit is elevated into vertical position as shown in Figure 4, there will be an opening across the lower end 68 of the movable unit as shown in Figure 4, and accordingly a hinged flap member 70, hinged by means of hinge 72 to the last floor board nearest the head end of the bed as seen in Figure 2, drops by means of gravity

to the position it occupies in Figure 4 when the movable unit is raised, thus serving to close the said opening which would otherwise appear at location 68 in Figure 4. The flap 70 also permits the cleaning out of the debris, dust and dirt which may accumulate inside the bed, by merely lifting the flap and using a small broom or brush for cleaning said debris.

When the movable unit of the bed is in elevated position, the foot end legs 46 and 48 are pivoted over to the position shown in Figure 4 so they do not project, the whole unit being supported on the four legs shown at the bottom of Figure 4, and hence the bed does not occupy any more space when folded up than a small end table or the like.

The bed can be made in dimensions to suit the individual dog or other animal. It keeps the dog out of the other furniture in the house, and is very handy at night when it can be let down in a moment, with a suitable mattress or pad normally resting on the floor boards 40. The mattress or pad remains against the floor boards when the bed is folded to upright position shown in Figure 4, so that it is all ready for the dog when the bed is opened out. I have found by actual use that this novel folding bed is a real saver of time and work in caring for a household pet such as a dog.

Although I have described a preferred embodiment of my invention in specific terms, it is to be understood that various changes may made in size, shape, materials and arrangement without departing from the spirit and scope of my invention as claimed.

I claim:

1. A folding bed comprising a vertical headboard having a forwardly projecting shelf on its lower end, having forwardly and rearwardly spaced leg members depending from opposite ends thereof for engaging a surface to support said head board in erect stationary position thereon, forwardly projecting relatively short side plates on said head board above said shelf, a mattress frame comprising relatively long side plates having their rearward ends at the outer sides of and horizontally pivoted to said short plates to swing from a horizontal position to a vertical folded position, a footboard connected to and between the forward ends of said long side plates, mattress support means on said frame extending between said long side plates and extending rearwardly from said footboard and terminating at its rear end at a point adjacent to the forward edge of said shelf while said mattress frame is in open horizontal position, mattress frame leg means depending from the forward end of said mattress frame for supportably engaging said surface, said mattress frame being sufficiently longitudinally elongated to place said footboard at a level above the upper end of said headboard when said mattress frame is folded upwardly to erect position.

along the forward side of said headboard, and releasable catch means having components cooperatively positioned on the upper edge of said headboard and on said footboard for holding said mattress frame in its erect folded position, the said rear edge of said mattress support means being vertically spaced from said shelf in the erect vertical folded position of said mattress frame so as to expose said shelf for cleaning out of debris deposited thereon by the upward folding of said mattress frame, and a closure plate hinged to depend from said rear edge of said mattress support while said mattress support is in its open horizontal position and to swing downwardly as said mattress frame is folded upwardly in a manner to conceal said shelf while said bed is in folded position.

2. In a folding bed, a horizontally disposed shelf, legs dependingly supported from said shelf for supporting the latter in spaced relation above a supporting surface, a vertically disposed head board arranged adjacent to one end edge of said shelf and secured thereto, a side plate arranged adjacent to each of the side edges of said shelf and secured thereto, a mattress frame positioned adjacent to the other end edge of said shelf and having one end mounted on said side plates for swinging movement from a horizontal position in alignment with said shelf to a vertical position in abutting relation with said head board, a foot board positioned adjacent to the other end of said mattress frame and secured thereto, a leg arranged underneath said foot board and connected thereto for swinging movement from a vertical supporting position in alignment with said foot board to a non-supporting position in abutting relation with said foot board, means carried by said head board and engageable with said foot board for positioning said mattress frame in abutting relation with said head board, and closure means hingedly connected adjacent to and spaced from said one end of said mattress frame to permit access to said shelf for cleaning out of debris deposited thereon when said mattress frame is in abutting relation with said head board.
